UNITED STATES PATENT OFFICE.

DANIEL J. HERTY, OF REVERE, MASSACHUSETTS.

FLUSH TANK.

Application filed June 22, 1921. Serial No. 479,534.

To all whom it may concern:

Be it known that I, DANIEL J. HERTY, a citizen of the United States, and resident of Revere, county of Suffolk, State of Massachusetts, have invented an Improvement in Flush Tanks, of which the following description, in connection with the accompanying drawing, is a specification, like characters on the drawing representing like parts.

This invention relates to improvements in flush tank constructions, and the object thereof is to provide a novel form of flush valve adapted to discharge the water from the flush tank.

A further object of the invention is to provide a non-leakable flush tank construction having a siphonic flush valve in which the water will automatically drain off through the discharge pipe if the liquid in the tank rises above a predetermined level.

A further object of the invention is to provide a flush tank construction having a siphon flush valve in which the siphonic action may be readily initiated.

A further object of the invention is to provide a simple and relatively inexpensive flush valve construction which may be readily installed in any usual flush tank and which when so installed will prevent overflow of the tank.

Other objects and features of the invention will more fully appear from the following description and the annexed drawings and will be pointed out in the accompanying claims.

In the drawings:

Fig. 1 is a vertical longitudinal sectional view of a flush tank equipped with a preferred form of siphonic valve embodying my invention, the usual ballcock being shown in elevation;

Fig. 2 is an end elevation of the outlet end of the discharge pipe which leads from the outlet leg of the siphon showing a preferred type of valve.

In usual flush tank constructions the liquid is maintained at a predetermined normal level by a ballcock and the water is drawn from the flush tank through a discharge pipe which is equipped with a valve adapted to be operated by a lever or other device and so constructed as to close automatically when the tank has been emptied. In such constructions, however, the leakage of the ballcock will cause the tank to over-

flow. Furthermore, in such constructions the valve frequently becomes corroded and either sticks or fails to seat properly so that there is an undesirable waste of liquid.

The present invention is designed to overcome such difficulties by providing a free flow of the liquid from the tank through a siphon which will discharge the liquid from the tank to a predetermined low level, after which the siphon will become broken and filled with air so that the valve and pump are normally dry.

A preferred embodiment of my invention is illustrated in the drawings as applied to a usual flush tank comprising a tank 1 having an inlet pipe 2 leading from a suitable source of supply and discharging through a pipe 3 which extends below the normal low level of the liquid in the tank so that the filling of the tank is substantially noiseless. The supply of water to the tank may be controlled through a ball-cock 4 operated by the usual float valve 5.

In accordance with my invention the liquid is discharged from the tank through a siphon having means preferably connected to a discharge leg for producing a partial vacuum in the siphon to initiate siphonic action.

As illustrated herein the siphon comprises an intake leg 6 and a discharge leg 7 connected at their upper ends by an inverted U-shaped pipe 8 having screw threaded connection at its end with the upper ends of the siphon legs 6 and 7. The siphon is so positioned in the tank that the crest 9 of the under wall of the U-shaped section 8 is slightly above the normal liquid level in the tank. The discharge leg 7 of the siphon is connected to a preferably horizontal pipe or conduit 10 which at its other end is connected to an elbow 11 extending through the bottom of the tank. The elbow 11 desirably is provided with an annular supporting flange 12 which rests upon the bottom of the tank. The end portion of the elbow section 11 desirably is provided with screw threads 13 which are engaged by a nut 14 which engages the bottom of the tank and serves to clamp the flange 12 firmly upon the bottom of the tank.

A suitable gasket 15 may be interposed between the flange 12 and the bottom of the tank to form a liquid-tight joint. The horizontal section 10 of the outlet pipe or conduit desirably is provided with an upwardly

extending boss 16 having internal screw threads 17 which are engaged by the external threads of a pump cylinder 18 which preferably extends vertically in parallelism with the legs 6 and 7 of the siphon. The cylinder 18 is provided with a piston 19 which is connected by a piston rod 20 to one end of an actuating lever 21 which is pivotally mounted upon a bracket 22 upon the tank and is operated by a cord 23 or any other suitable means. The horizontal pipe 10 desirably is provided with a suitable valve which is located beyond the pump cylinder 18.

15 In the preferred construction illustrated herein the end of the horizontal section is provided with a valve seat 24 which, as illustrated herein, is in the form of a bushing having on its outer end a flap valve seat preferably slightly inclined from the vertical. A flap valve 25 is pivotally connected by a suitable hinge 26 to the valve seat and normally is held by the influence of gravity against the valve seat.

20 In the operation of the device the ball-cock is set to maintain the liquid in the tank at a predetermined level 27 which is slightly below the crest 9 of the lower wall of the inverted U-shaped conduit which connects the legs 6 and 7 of the siphon. If the level of the liquid rises above the crest 9, liquid will flow by gravity to the siphon without producing siphonic action so that the level of the liquid in the tank will never 25 rise beyond the siphon and inasmuch as the siphon is located below the top of the tank all danger of overflow of the tank is prevented.

25 When it is desired to discharge the contents of the tank the actuating lever 21 is operated by pulling upon the cord 23. This causes the piston 19 to be raised within the cylinder thus creating a partial vacuum in the discharge leg of the siphon so that the pressure of the air upon the surface of the liquid will cause it to flow through the siphon and initiate the siphonic action. As soon as the siphonic action is commenced the actuating lever may be released and the 30 suction of the water will cause the piston to be drawn back to its original position. The liquid will then flow through the siphon until the level of the liquid reaches the lower end of the intake leg of the siphon whereby 35 entrance of air into the intake arm of the siphon will break the siphonic action. The tank may then be refilled.

40 Preferably a check valve, such as that above described, is provided in the discharge conduit beyond the pump so that it will be only necessary to create a partial vacuum in the short section of the discharge pipe and the siphon to initiate the siphonic action. However, the presence of such a 45 valve is not absolutely essential if the dis-

charge pipe leads to a water sealing chamber.

The construction thus illustrated and described is very simple and inexpensive since all of the parts are usual types of pipe fittings except the horizontal section of the discharge pipe which is relatively short and inexpensive to manufacture.

45 It will be noted that the cylinder in which the piston operates is always dry; consequently, there will be no deterioration of the pump from the presence of acids, alkali, or other impurities in the liquid.

50 It will also be noted that the siphon is normally filled with air and also operates to discharge liquid after the siphonic action is initiated and until the lower end of the siphon is exposed to the air by the lowering of the liquid level.

55 It will be understood that the embodiment of the invention disclosed herein is of an illustrative character and is not restrictive; and, that various modifications in construction and arrangement of parts may be made within the spirit and scope of the following 60 claims.

Having thus described my invention, what I claim as new, and desire to secure by Letters Patent, is:

1. A flush tank construction comprising a 65 tank, a liquid supply, means for maintaining the liquid at a normal predetermined level in said tank, a siphon having its intake leg extending into said tank below said normal liquid level, a dry pump comprising a 100 cylinder connected to the delivery leg of said siphon and a piston reciprocable in said cylinder operable to create a partial vacuum in said siphon and thereby to initiate siphonic action and a check valve located 105 beyond said pump adapted to be closed by the suction action of said pump.

2. A non-leakable flush tank construction comprising a tank, a liquid supply, means for normally maintaining the liquid at a 110 predetermined level in said tank, a siphon in said tank having its intake leg extending below the normal level of the liquid and the crest of the siphon slightly above said liquid level, a discharge pipe having a horizontal 115 section connected to the outlet leg, a dry pump comprising a cylinder communicating with said horizontal conduit, a piston reciprocable in said cylinder and means for actuating said piston to initiate siphonic 120 action.

3. A non-leakable flush tank construction comprising a tank, a liquid supply, means for normally maintaining the liquid at a 125 predetermined level in said tank, a siphon in said tank having its intake leg extending below the normal level of the liquid and the crest of the siphon slightly above said liquid level, a discharge pipe having a horizontal section connected to the outlet leg, a dry 130

5 pump comprising a cylinder communicating with said horizontal conduit, a piston reciprocable in said cylinder, means for actuating said piston and a normally seated valve at the discharge end of the horizontal section of said discharge pipe adapted to be tightly closed by the suction of said pump and thereby to facilitate the initiation of the siphonic action.

10 4. A non-leakable flush tank construction comprising a tank, a liquid supply, means for normally maintaining the liquid at a predetermined level in said tank, a siphon in said tank having its intake leg extending 15 below the normal level of the liquid and the crest of the siphon slightly above said liquid

level, a discharge pipe having a horizontal section connected to the outlet leg, a dry pump comprising a cylinder communicating with said horizontal conduit, a piston in said cylinder, means for actuating said piston, an inclined valve seat at the end of the horizontal section of said discharge pipe and a valve pivotally mounted in position to be normally seated on said valve seat by the action of gravity and adapted to be tightly closed by the suction action of the pump and thereby to facilitate the initiation of the siphonic action.

In testimony whereof, I have signed my name to this specification.

DANIEL J. HERTY.
